UNITED STATES PATENT OFFICE.

JOHN I. HOKE, OF SOUTH BEND, INDIANA.

SULKY-PLOW.

SPECIFICATION forming part of Letters Patent No. 230,014, dated July 13, 1880.

Application filed April 16, 1880. (No model.)

To all whom it may concern:

Be it known that I, JOHN I. HOKE, a citizen of the United States, residing at South Bend, in the county of St. Joseph and State of Indiana, have invented certain new and useful Improvements in Sulky-Plows; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

My invention relates to improvements in sulky-plows; and the objects of my improvements are, first, to provide means by which the plow may be turned around at the ends of the furrows by the direct draft of the horses, instead of by pressure upon the tongue thereof; second, to provide devices for locking the tongue in a proper position for plowing and for unlocking it when the plow is to be turned around; third, to provide the requisite means for regulating the depth that the plow shall enter the earth; fourth, to provide the requisite means for controlling the position of the point of the plow so that it may enter the earth to a uniform depth, whether used in hard or soft ground; fifth, to provide the requisite means for allowing one of the wheels to run upon the plowed ground and carry but a small portion of the weight of the machine, while the other runs upon the solid ground and carries the most of the weight; sixth, to provide the requisite devices for regulating the width of the furrow turned by the plow. I attain these objects by the mechanism illustrated in the accompanying drawings, in which—

Figure 1 is a plan view of a sulky-plow, showing the wheels, the jointed axle, the slide for adjusting the depth of the plow in the earth, the devices for regulating the position of its point in hard and soft ground, the plow, a portion of the tongue, and the device for automatically locking and unlocking it. Fig. 2 is a sectional elevation, showing the parts above enumerated. Fig. 3 is a rear view, showing the means of adjusting the sections of the axle and for regulating the depth of the plow

in the earth. Fig. 4 is a detached view, showing the devices for attaching the tongue to the beam and for latching it thereto, the devices to which the team is attached, and the devices for automatically latching and unlatching the tongue. Fig. 5 is a section showing the plates to which the tongue is attached and a portion of the latch which holds it in position; and Fig. 6 is a plan and side view of the clevis, to which the power for driving the plow is attached.

Similar letters refer to similar parts throughout the several views.

In constructing a sulky-plow with my improvements applied thereto I use two wheels, A A, of any approved form and material. These wheels are allowed to turn freely upon their axle, and are held thereon by means of a nut screwed upon said axle, or in any other manner.

The axle consists of two sections, B and B', that lettered B passing through the wheel and inward therefrom to the point where it joins section B'. Near the wheel-seat of B there is provided a vertical arm, B², in which there is formed a T-shaped slot or groove, and in which there is placed a slide, B³, which has upon its inner surface a loop, B⁴, through which the beam B⁵ of the plow passes, and by which the rear end of said beam and the plow proper are carried.

To the upper portion of arm B² of the axle there is affixed a lug, B⁶, to which there is pivoted a lever, B⁷, to the short arm of which a link, B⁸, is attached, the opposite end of which is pivoted to the beam B⁵.

The lever B⁷ being near the seat of the operator, he can at any time change the position of its outer end by raising or lowering it, and thus cause the slide B³ and loop B⁴ to be lowered or raised and the depth of the furrow regulated in ordinary ground.

From the arm B², above described, the section B of the axle extends to a point about midway between the wheels A A, where it is provided with a vertically-arranged T-shaped end, B⁹, as shown in Fig. 1. At this point it joins section B' of the axle, which at its inner end is provided with an arm, B¹⁰, and with a

groove which receives the end of arm B. To the section B, near where it joins B', there is affixed a lug to which a lever, C, is pivoted, the short arm of which carries a link, C', the 5 lower end of which is secured to the section B of the axle in the manner shown in Fig. 3.

The lever C is provided with a sliding dog, which engages with a toothed sector formed on section B' of the axle, the arrangement of 10 the parts last described being such that the operator can raise or lower section B' of the axle by changing the position of lever C, and thus place a greater or less amount of weight upon the different wheels of the plow without 15 changing the position thereof in the earth.

In making provision for controlling the position of the point of the plow, and thus its tendency to run deeper in soft than in hard earth, there is attached to the forward end of 20 the beam a bracket, D, which has pivoted to it a plate, D', in the upper surface of which there is a transverse groove, (shown in Fig. 2.) Into this groove there is fitted a projection formed upon a disk which is capable of being 25 moved laterally in said groove. Upon the top of disk D² there is placed another disk, D³, upon the upper surface of which there are formed ribs, between which the end of the tongue passes, as shown in Figs. 1 and 4.

30 For the purpose of holding the devices just alluded to and the tongue of the machine in their proper positions on the plate D', a bolt, D⁴, is passed through them. This arrangement of parts provides the necessary means 35 for regulating the width of the furrows by adjusting the parts upon the plate and securing them in their adjusted positions by the bolt D⁴, the wider furrow being cut by sliding the disks and the tongue of the machine to the 40 right, and the narrower by sliding them to the left. Upon the upper surface of the plate D' there is formed or affixed a toothed sector, D⁵, to which is pivoted a lever, D⁶, the short arm of which carries a link, D⁷, the lower end of 45 which is attached to the pivoted plate D', which turns upon a bolt passing through it and the vertical flange of bracket D. The arrangement of these parts is such that upon approaching hard earth the operator can, by 50 pressing backward the upper end of lever D⁶, force the point of the plow downward, and thus cause it to enter the earth to the same depth that it did in softer ground, and upon coming to the softer parts of the field he can, 55 by changing the lever to its former position, prevent the plow from entering too deep, the lever being furnished with a latch for holding it in its adjusted position.

Another important feature of my improvements 60 consists in the means employed for enabling the operator to turn the plow around by the direct draft of the horses, instead of pushing the tongue around by pressing against it, as is usual. For the accomplishment of this 65 object there is formed upon the under surface

of the bracket D downwardly-projecting arms E, E', which are provided with holes for the adjustment therein of a peculiarly-formed clevis, E', which consists of a bar of metal with ears projecting from its rear edge, which have holes 70 through them for attaching it to the arms of bracket D. A view of this device is shown in Fig. 6.

When the plow is in use the double-tree is attached to the clevis, and consequently when 75 said plow is being drawn forward the clevis is drawn up into the position shown in Fig. 1; but upon arriving at the end of the furrow, and the draft being stopped, it will fall down into the position shown in Fig. 4. This device 80 is made to operate a slide, F, for holding the tongue in line with the path of the machine when in motion and for releasing the same when turning around, so that said tongue may be placed at a right or any other angle there- 85 to made necessary in turning. For the accomplishment of this purpose there is formed in the head of bolt D⁴ a passage, through which the lower horizontal portion of slide F passes, its vertical portion being provided with a short 90 horizontal projection, F', which enters a notch in the disk D², which prevents the bolt from turning around. Just above the portion F' there is formed a wedge-shaped projection on slide F, which, when the plow is being drawn 95 forward, enters a notch formed in the disk to which the tongue is fastened, but which, when the strain is relieved, falls back and allows the tongue to be turned, as above stated. This slide F is operated by means of a pin or stud, 100 F², which is made to project therefrom down through a slot formed in the end of clevis E', the arrangement being such that when force is being applied to draw the plow forward the 105 clevis will be drawn up into a horizontal position, which will have the effect to press the slide F forward and lock the tongue in a line with the path of the machine; but when the force ceases to be applied the clevis will fall down into an angular position, which will carry 110 the slide rearward and unlock said tongue, and leave it free to turn at a right angle to its former position, and thus allow the plow to be turned by the draft of the animals, as 115 above stated.

Having thus described my improvements, what I claim, and desire to secure by Letters Patent, is—

1. The combination of beam B⁵, bracket D, plate D', the disks D² and D³, and bolt D⁴, or 120 their equivalents, the clevis E', the locking-slide F, arm F², and the tongue of the machine, the parts being constructed and arranged for joint operation, substantially as set forth, whereby the plow can be turned around by 125 the direct draft of the team.

2. In combination with the beam of a plow, a bracket, D, an adjustable plate, D', a lever, D⁶, and link D⁷, the parts being arranged for operation, substantially as described, where- 130

by they may be made to give the proper dip or position to the point of the plow and to regulate the same with reference to hard and soft ground, as described.

5 3. The combination of the adjustable plate D', having a groove in its upper surface, the disk D², having a projection upon its under surface, and the bolt D⁴, whereby the width of the furrow cut by the plow can be regulated

by a transverse movement of the disk upon to the plate, as described.

In testimony whereof I affix my signature in presence of two witnesses.

JOHN I. HOKE.
